UNITED STATES PATENT OFFICE.

JOHN H. O'BRIEN, OF FORT WAYNE, INDIANA, ASSIGNOR OF ONE-HALF TO JESSE E. MILLS, OF FORT WAYNE, INDIANA.

SHOE-REPAIR JACK.

1,210,355.

Specification of Letters Patent. Patented Dec. 26, 1916.

Application filed April 5, 1916. Serial No. 89,190.

To all whom it may concern:

Be it known that I, JOHN H. O'BRIEN, a citizen of the United States, residing at 827 Barr street, Fort Wayne, in the county of Allen and State of Indiana, have invented certain new and useful Improvements in Shoe-Repair Jacks, of which the following is a specification.

This invention relates to an improvement in shoe repair jacks.

The primary object of the invention is to provide a shoe repair jack in which the last may be moved into any desired position and still be convenient to the operator.

A further object of the invention is to provide a construction in which the last may be quickly adjusted and after having been adjusted locked against movement.

Another object of the invention is to provide a structure in which the support for the adjustable last arm is itself adjustable whereby the last and its supporting structure may be moved with respect to the base.

With the above and other objects in view, the present invention consists in the combination and arrangement of parts hereinafter more fully described, illustrated in the accompanying drawings, and particularly 80 pointed out in the appended claims, it being understood that changes may be made in the form, size, proportion and minor details without departing from the spirit or sacrificing any of the advantages of the invention.

In the drawings Figure 1 is a side elevation. Fig. 2 is a front elevation. Fig. 3 is a plane view of the locking means for the last arm, and Fig. 4 is a view of the terminal of the last supporting arm.

In the drawings 10 designates a tubular base common in jacks of this type. The upper open end of said base is provided with a slot 11 and extending from said tubular member on each side of said slot is a lug 12, said lugs being formed with alining apertures 13, one of which is threaded. These lugs receive a screw 14 by means of which the open end of the tubular base may be contracted. Mounted upon the base 10 is an L-shaped arm 15. This arm is provided at one end with the right angle extension 16. This extension is reduced and the shoulder 17 formed thereby engages the tubular member when the reduced portion of the exten-

sions is inserted within the open end of the same. The vertically extending portion 18 of the arm is terminally provided with a bearing 19 which is split, the same being provided with a plurality of lugs 20 through 60 which an adjusting screw 21 passes whereby the bearing may be contracted.

A second L-shaped arm 22 is provided, the horizontally extending portion 23 of said arm terminating in the split ring 24 formed with lugs 25 whereby the split ring may be contracted. The vertically extending portion of the arm is formed with the right angle extension 25 which is reduced at 26 terminating in a squared reduced extension 27. 70 The rounded reduced portion 26 is adapted to enter the split bearing 19 of the arm 15, the squared portion 27, extending beyond said arm. Mounted on said squared portion is a toothed disk 28. The bearing 19 is 75 formed with spaced lugs 29 between which is pivoted a dog 30, said dog being disposed to engage within the notches of the toothed wheel 28. It will be noted by this arrangement that the arm 22 is free to rotate within 80 the bearing 19 and that when the same has been rotated to the desired position, it being understood that during said rotation the dog 30 has been lifted, said dog is dropped into one of the notches of the disk 28 and the 85 arm locked against further movement.

A last support 31 of the usual construction is supported within the split ring carried by the arm 22. The last is maintained in position on the support by the strap 32 90 which embraces the same and which passes through an opening 33 formed in a latch member 34 which is pivotally supported on the ears 35 of a collar 36 which embraces the last standard adjacent its base.

With a construction of this character the shoe may be brought into any desired position and its support firmly held against displacement. Thus the workman may stand directly in front of the jack at all times and in an upright position. It will also be noted that the arm 18 may be rotated with respect to the base 10 by loosening the screw 14, thus allowing the work to be conducted immediately above the supporting base irrespective of the position to which the arm 15 may be swung.

The many advantages of construction of this character will be clearly apparent as it will be noted that the same not only pro-

vides a jack which may be readily adjusted in various positions, but that the structure is simple and not liable to get out of order. It will also be seen that the device may be 5 easily and economically manufactured and that the various parts may be readily assembled.

What I claim is:

1. A lasting jack comprising a base, an 10 arm rotatably supported on the base, said arm having a vertical extension, and a second arm rotatably mounted on the said extension to swing about a horizontal axis and in a plane parallel with the plane of the 15 vertical extension.
2. A lasting jack comprising a base, an arm rotatably supported on the base, said arm having a vertical extension; a second arm rotatably mounted on the said extension to swing about a horizontal axis and in a plane parallel with the plane of the 20 vertical extension, and means for locking said second arm against movement.
3. A shoe repairing jack comprising a 25 base having a tubular extension, one end of said extension being open the extension adjacent said open end being slotted, means for contracting said open end, an L-shaped arm having an extension received within the 30 open end of the base, the terminal of said arm remote from said extension being split to provide a bearing, a second L-shaped arm having an extension received within said bearing, the end of said extension projecting 35 beyond the bearing and being squared; a notched disk arranged on said squared end, a dog carried by the bearing and engaging in the notches of said disk and a last support carried by said second mentioned arm.
4. A lasting jack comprising a base, an 40 arm rotatably supported on the base, said

arm having a vertical extension, a second arm rotatably mounted on the said extension to swing about a horizontal axis and in a plane parallel with the plane of the 45 vertical extension, means for locking said second arm against movement and a last support carried by the second arm and adjustable thereon.

5. A lasting jack comprising a base, an 50 arm rotatably supported on the base, said arm having a vertical extension, a bearing formed at one end of said extension, and a second arm rotatably mounted on the said extension to swing about a horizontal axis 55 and in a plane parallel with the plane of the vertical extension, said second arm being formed with an extension adapted to be received within the bearing of the vertical extension, whereby said second arm is rotatably mounted on the said vertical extension.

6. A lasting jack comprising a base, an 60 arm rotatably supported on the base, said arm having a vertical extension, a bearing formed at one end of said extension, a second arm rotatably mounted on the said extension to swing about a horizontal axis and in a plane parallel with the plane of the 65 vertical extension, said second arm being formed with an extension adapted to be received within the bearing of the vertical extension, whereby said second arm is rotatably mounted on the vertical extension, means for locking the second arm against 70 movement, and a last support carried by the 75 second arm and adjustable thereon.

In testimony whereof I affix my signature in the presence of two witnesses.

JOHN H. O'BRIEN.

Witnesses:

L. J. LIBBING,
AUGUST G. BUG.
